UNITED STATES PATENT OFFICE

JOHN F. GRACE, OF ARLINGTON, NEW JERSEY, ASSIGNOR TO WORTHINGTON PUMP AND MACHINERY CORPORATION, OF NEW YORK, N. Y., A CORPORATION OF VIRGINIA

EXHAUST CONNECTION FOR CONDENSERS

Application filed December 12, 1928. Serial No. 325,624.

This invention relates to steam condensers of the surface type and more particularly to an exhaust steam connection between the engine, such as a steam turbine, and the condenser.

An object of the invention is to provide an exhaust connection which will prevent the formation of vortex in the steam during its passage to the condenser and which will guide or straighten the passage of the steam so as to facilitate its equal distribution through the condenser and prevent the larger part of the steam from flowing towards the generator side of the condenser, as is the normal tendency of the steam.

A further object of the invention is to provide an exhaust connection as specified in which an expansion or yieldable joint is embodied which relieves or reduces the atmospheric thrust on the top of the turbine.

With these objects in view, the invention consists in various features of construction and combination of parts, which will be first described in connection with the accompanying drawings, showing an exhaust connection for condensers of the preferred form embodying the invention, and the features forming the invention will be specifically pointed out in the claims.

Fig. 1 is a section through the improved exhaust steam inlet connection showing it connected to a turbine and a condenser.

Fig. 2 is a view partly in section and partly in side elevation of an alternate construction of the exhaust steam inlet, and

Fig. 3 is a section through a further modified or alternate form of the exhaust steam connection showing it applied in connection with a vertical condenser.

Referring more particularly to the drawings, the improved exhaust connection 1 is shown connected to an exhaust steam condenser 2 of any approved construction, it being understood that the exhaust steam inlet connection may be applied to surface condensers of any approved type, without departing from the spirit of this invention.

The connection 1 which serves to guide the steam from the exhaust of the turbine 3 into the condenser has its walls 4 inclining in-

wardly from the inlet end of the connection for a predetermined distance which gradually reduces the cross sectional area of the connection to the predetermined point. From the innermost point of inward tapering of the walls 4 they taper outwardly for a predetermined distance either to their connection with the condenser 2 as shown in Fig. 1 of the drawings or to a predetermined point as desired. The walls 4 are curved as shown at 5 to form curved junctions between the inward and outward tapering portions of the walls to prevent the formation of abrupt shoulders or edges which might have a tendency to cause eddies in the steam during its passage to the condenser.

Owing to the manner in which the exhaust steam is discharged from the turbine 3 the natural tendency of the steam is to go towards one side of the condenser resulting in unequal distribution of the steam over the condenser area. However with the walls 4 of the exhaust connection 1 tapered as above specified, the steam, on engaging the inwardly tapering portions will be deflected transversely across the exhaust connection, causing its distribution throughout the connection and its equal distribution to the condensing surface within the condenser shell and eliminating sinuous travel of the steam as well as preventing the forming of vortex in the steam.

In Fig. 2 of the drawings, an alternate arrangement of the exhaust connection is shown, which is particularly designed for a low head system and in this modified form the connection is made to provide a plurality of passages, such as 10 and 11 for the steam from the turbine exhaust 12 into the condenser 13. Each of the passages 10 and 11 have their walls 14 inclining or tapering inwardly from the steam entrance to a predetermined point where they are connected by means of an expansion joint 15 to the outwardly tapering or inclining section 16 of the walls, thereby providing a plurality of exhaust connections for guiding the exhaust steam from the turbine into the condenser, which are of gradually decreasing cross sectional area for a part of their length, and of gradually increasing cross sectional area for

another part of their length, while the portions confined within the expansion joint 15 are of substantially uniform cross sectional area. The expansion joint 15 permits relative movement of the condenser or turbine without transmission of such movement from one to the other, relieves or reduces the atmospheric thrust on the top of the turbine casing and permits more rigid mounting of the condenser 13.

In Fig. 3 of the drawings, a vertical type of surface condenser 20 is shown with an exhaust connection 21 between the condenser 20 and the turbine 22 so that the steam will be guided laterally into the condenser 20. The exhaust connection 21 embodies the inlet section 22, the walls of which taper inwardly for the major portion of the length of this section. The section 22 has a tight slip joint connection 23 with the section 24 of the exhaust connection 21. The walls 25 of the section 24 taper outwardly from the slip joint 23 to the other points of connection with the section 26 of the exhaust connection, providing substantially a venturi, that is a converging diverging nozzle, for changing the flow of the exhaust steam of the turbine from an uneven and sinuous flow to a parallel flow of even velocity, consequently facilitating the distribution of the steam to the deflectors 27 which change the direction of flow of steam and guide it into the condenser 20.

From the foregoing description, taken in connection with the accompanying drawings, it will be apparent that in each and every one of the forms of exhaust connection shown in the drawings, a nozzle or passage way of converging diverging cross sectional area is provided which will straighten the flow and distribute the steam to cause its proper distribution in the condenser.

It will be understood that the invention is not to be limited to the specific construction or arrangement of parts shown but that these may be modified widely within the invention defined by the claims.

What is claimed is:

1. An exhaust steam inlet connection for surface condensers including a shell having its walls tapering inwardly for a predetermined distance from the inlet of the connection and tapering outwardly for a predetermined distance from the innermost point of the inward tapering, and an expansion joint forming a junction between the inward and outward tapering portions of the walls.
2. An exhaust steam inlet connection for surface condensers including a shell having its walls tapering inwardly for a predetermined distance from the inlet of the connection and tapering outwardly for a predetermined distance from the innermost point of the inward tapering, and a moveable joint forming a junction between the inward and outward tapering portions of the walls.

3. The combination with a surface type steam condenser, of an exhaust connection for guiding the steam into the condenser, having its walls tapering inwardly for a predetermined distance from the inlet of the connection and tapering outwardly from the innermost point of the inward tapering to its outlet into the condenser, and a moveable joint forming the junction between the inward and outward tapering portions of the walls.

4. The combination with a surface type steam condenser, of an exhaust connection for guiding steam into the condenser embodying a plurality of passages, the walls of said passages tapering inwardly for a predetermined distance from the inlet of the connection and tapering outwardly for a predetermined distance from the innermost point of inward tapering of the walls.

5. The combination with a surface type steam condenser, of an exhaust connection for guiding steam into the condenser embodying a plurality of passages, the walls of said passages tapering inwardly for a predetermined distance from the inlet of the connection and tapering outwardly for a predetermined distance from the innermost point of inward tapering of the walls, and an expansion joint forming a junction between the inward and outward tapering portions of said walls.

6. An exhaust steam inlet connection for surface condensers of converging, diverging cross section area composed of a plurality of sections and a movable joint connecting said sections.

7. An exhaust steam inlet connection for surface condensers of converging, diverging cross section area and an expansion joint embodied in said exhaust steam inlet connection.

8. An exhaust steam inlet connection for surface condensers of converging, diverging cross section area and composed of a plurality of sections and a movable joint connecting certain of said sections, to permit relative movement of such sections and prevent transmission of thrusts from one section to the other.

In testimony whereof I affix my signature.
JOHN F. GRACE.
